United States Patent Office

Des. 226,537
Patented Mar. 20, 1973

226,537

FREIGHT CAR BODY

Jack Hickman, 5766 Fair Oaks,
Carmichael, Calif. 95608

Filed Mar. 1, 1971, Ser. No. 119,995

Term of patent 14 years

Int. Cl. D12—03

U.S. Cl. D66—1

Fig. 1

Fig. 2

Fig. 5

Fig. 3

Fig. 4

FIG. 1 is a top plan view of the freight car body showing my new design;

FIG. 2 is an elevation view of one side thereof;

FIG. 3 is a bottom plan view thereof;

FIG. 4 is an elevation view of the other side thereof;
and

FIG. 5 is an end elevation view thereof.

I claim:

The ornamental design for a freight car body, as shown and described.
